POURING CANISTER

Jack Fairchild Fleming, Yonkers, N. Y., assignor
to Sterling Plastics Company, Union, N. J., a
corporation of New Jersey

Application September 22, 1950, Serial No. 12,304

Term of patent 14 years

(Cl. D44—6)

To all whom it may concern:

Be it known that I, Jack Fairchild Fleming, a citizen of the United States, residing at Yonkers, in the county of Westchester and State of New York, have invented a new, original, and ornamental Design for a Pouring Canister, of which the following is a specification, reference being had to the accompanying drawing, which forms a part hereof and in which:

Figure 1 is a front elevational view of a pouring canister embodying my new design;

Figure 2 is a side elevational view;

Figure 3 is a rear elevational view; and

Figure 4 is a top plan view thereof.

The lid of the canister is shaded to denote a

color contrasting with the color of the canister body.

I claim:

The ornamental design for a pouring canister, substantially as shown and described.

JACK FAIRCHILD FLEMING.
